US0D1108074S

(12) United States Design Patent (10) Patent No.: US D1,108,074 S
(45) Date of Patent:  Jan. 6, 2026

(54) GLOVE

(71) Applicant: WonderGrip (CHINA) CO., Ltd.,
Dongtai (CN)

(72) Inventors: Guoda Dai, Shanghai (CN); Menglu Dai, Shanghai (CN); Genkai Watanabe, Chiba (JP); Wei Wen, Jiangsu (CN)

() Term: 15 Years

(21) Appl. No.: 35/523,100

(22) Filed: Oct. 15, 2024

(80) Hague Agreement Data

Int. Filing Date: Oct. 15, 2024

Int. Reg. No.: DM/242037

Int. Reg. Date: Oct. 15, 2024

Int. Reg. Pub. Date: Nov. 29, 2024

(51) LOC (15) Cl. 02-06

(52) U.S. Cl.

USPC D2/617

(58) Field of Classification Search

USPC D2/610, 611, 617-619, 621, 622;
D29/113, 116.1, 116.2, 117.1, 117.2, 119

CPC A63B 71/146; A63B 71/141

See application file for complete search history.
